UNITED STATES PATENT OFFICE

2,181,701

INJECTOR

Hermann E. F. C. Lingenbrink, Philadelphia, Pa., assignor to William Sellers & Company, Incorporated, Philadelphia, Pa., a corporation of Pennsylvania

Application June 30, 1939, Serial No. 282,041

9 Claims. (Cl. 103—265)

This invention relates to an improvement in connection with injectors such as are used for supplying feed-water to a boiler and, more particularly, in connection with injectors adapted 5 to operate wholly or partially with exhaust steam.

The invention here relates more particularly to apparatus for the control of supply to an injector of exhaust steam from an engine or, in the alternative, when sufficient exhaust steam is 10 not available, of auxiliary live steam at suitably reduced pressure.

Still more particularly, in accordance with this invention the supply to an injector of exhaust or auxiliary live steam will be primarily controlled 15 by means operable by exhaust steam pressure, such means being under control of live steam pressure in order to insure that no starting auxiliary live steam will be supplied to the injector initially. Again, means are provided to delay operation of the means operable under exhaust 20 steam pressure in order to insure that on the operation thereof there will be an adequate supply of exhaust steam for the injector.

The improvement according to this invention, while adaptable generally for use in connection 25 with injectors of the type operating wholly or partly on exhaust steam, will be found to have exceptional advantage and merit in connection with injectors of the feed-water heating type. Such injectors are well known and in general 30 comprise a set of heating tubes to which water and steam at relatively low pressure are supplied, and a set of forcing tubes receiving the delivery from the heating tubes into which live steam is supplied for delivery into a boiler.

35 Further and more specific details with respect to this invention will appear from the following description of a preferred embodiment of the invention as shown in the accompanying drawings, in which:

40 Figure 1 is a cross-sectional view of an auxiliary live steam valve in association with operating mechanism adapted for operation under exhaust steam pressure.

Figure 2 is a side view, partly in section, of 45 mechanism for automatically controlling the supply of exhaust steam or, in the alternative, auxiliary live steam, to an injector.

Figure 3 is a cross-sectional view of mechanism operable, under the influence of live steam, for 50 control of the supply of operating exhaust steam to the mechanism shown in Figure 1.

Figure 4 is a diagrammatic side view of a 55 locomotive equipped with feed-water heater type of injector mechanism for the control of a supply of exhaust steam or, in the alternative, of

auxiliary live steam to the heating tubes of the injector.

Referring now more particularly to Figure 4, 1 indicates a locomotive provided with an injector 2. The injector may be of any well known type operating wholly or partly on exhaust steam. As shown the injector is of the type shown in United States Patent Nos. 1,539,319 and 1,683,784 having a set of heating tubes 3 arranged to deliver into a set of forcing tubes 4, which in turn 10 deliver to the boiler of the locomotive through a conduit 5. The heating tubes 3 are supplied with water through a conduit 6 under control of a valve 7, while the forcing tubes 4 are provided with live steam from the locomotive boiler 15 through a conduit 8 under control of a starting valve 9. Exhaust steam from the locomotive cylinder when available, as when steam is in the cylinder, is supplied to the tubes 3 through a conduit 10, connected to the exhaust conduit from the cylinder and to the heating tubes 3. The conduit 10 also serves to supply auxiliary live 20 steam to the heating tubes in lieu of exhaust steam when steam is not on the cylinder and there is hence no exhaust available.

The supply to the heating tubes of exhaust or, in the alternative, of auxiliary live steam when exhaust is not available, is effected automatically by means actuated by exhaust steam pressure and controlled by live steam pressure. Such means are also so arranged that the injector will always 25 be started with auxiliary live steam and so that auxiliary live steam will always be supplied to the injector unless and until adequate exhaust steam is available. Such means included in the control device, indicated at 12, Figure 4, are illustrated 30 in detail in Figures 1-3 and will now be described with reference, more particularly, to those figures.

Referring now more particularly to Figure 2, 35 the mechanism for controlling the supply of exhaust or auxiliary steam to the injector is let into the conduit 10, between the injector and the exhaust pipe from the engine cylinder. The control mechanism comprises a live steam valve, for the admission of auxiliary live steam to the conduit 10, under the control of exhaust steam pressure, indicated at A, Figure 2 and detailed in Figure 1; a valve for controlling the admission of exhaust steam to the mechanism A under the control of live steam pressure, indicated at B, 40 Figure 2 and detailed in Figure 3, and mechanism 45 operable under live steam pressure for controlling the supply of exhaust steam to the injector through conduit 10, shown in detail at C in Figure 2.

55

The mechanism A comprises a casing 13 connected with the locomotive boiler through the starting valve 9 by a conduit 14 and communicating with the interior of conduit 10 through a passage 15, provided with lateral outlets 16, the size of which may be varied by adjustment of a choke member 17. The passage of live steam from conduit 14 into conduit 10 is controlled by a live steam valve 18 within the casing 13. The valve 18 is double headed, the upper head 18' seating on a seat 19, and being larger than the lower head 18'' which seats on a seat 19' and controls communication between conduit 14 and conduit 10. The head 18' is also provided with an upper seating surface 20 adapted, when the valve is open, to seat on a seat 21. The valve stem 22 extends through a guide 23, bears on the end of a stem 24, which extends through a guide 25 and connects to the underside of a disc 26, which in turn bears on the underside of a circular diaphragm 27 secured within the casing at its edges. A chamber 70 is formed above the upper head 18' and a chamber 71 is formed below the lower head 18''. The chambers 70 and 71 are connected by means of a passage 72 so that when valve 18 is opened the pressure below head 18'' and above head 18' is balanced.

The stem 24 is provided with spaced grooves 28 within the guide 25 which tend to catch condensate, from steam which may pass the valve stem 24 and enter the guide 25, and which serves to lubricate the stem 24. Between the guide 23 and the guide 25 is a space which is vented to conduit 10 through a passage 29 for the escape of any live steam passing the valve stem 22.

Within the casing 13 and above the diaphragm 27 is a chamber 30 connected to the exhaust conduit 10, ahead of the exhaust control valve mechanism C, through a conduit 31. The passage of exhaust steam through conduit 31 is controlled by the mechanism B (Figure 3), which comprises a valve 32 having a stem 33 and normally held on its seat 34 by a spring 35. The lower end of the stem 33 extends in a cylinder 36, provided at its bottom with a drain plug 37, and containing a piston 38. A conduit 39 connects the lower end of the cylinder 36 with the live steam conduit 14. The upper end portion of the piston 38 is reduced, as shown at 40 and passages 41, 41 opening laterally through the reduced portion 43 are provided in the body of the piston and are controlled by a ball check 42, which normally rests in open position on a pin 43.

In the bottom of the chamber 30, over the center of the diaphragm 27, is an aperture 44, adapted to be throttled by the throttling member 45. The member 45 comprises a head having a horizontal passage 46 extending through it and with which communicates a vertical passage 47 leading to a chamber 48 opening into the aperture 44 through apertures 49 in its bottom.

A hollow stem 50 extends upwardly from the member 45 into a tubular guide 51. The stem adjacent the member 45 is provided with apertures 52 for drawing off condensate.

The area within the casing above the diaphragm and outside of the chamber 30 may be drained through the passage 52 closed by a threaded plug 53.

The mechanism C for controlling the supply of exhaust steam to the injector, as shown in Figure 2, comprises a valve 53 adapted in open position to permit the passage of exhaust steam through conduit 10 to the injector and in closed

position to prevent the passage of auxiliary steam to the exhaust pipe of the engine, as when live steam valve 18 is open.

The valve 53 is connected to piston 54 in the cylinder 55, to which live steam is admitted when the valve 18 is opened through passages 56 in the live steam choke device 17. The valve is also connected to a cup 57, the flange 58 of which serves as an abutment for one end of the coiled spring 59, the other end of which connects with the casing 60. Within the cup is a fixed piston 61, provided with an aperture 62. The piston 61 is supported from the casing by a rod 64 and the cup is filled to a point over the piston with oil, as in Figure 2.

The operation of the embodiment of this invention will, it is believed, be made clear by the following description:

Assuming the mechanism to be carried by a locomotive, the function of the injector being to supply the locomotive boiler with preheated water. When the locomotive is standing and the injector is shut off by closure of the starting valve 9, the live steam valve 18 will be in the closed position shown in Figure 1 and the exhaust steam control valve 53 will be in the open position shown in Figure 2. The valve 32, which controls the flow of exhaust steam to the chamber 30 above the diaphragm 27 through the conduit 31 will be in closed position, as shown in Figure 3.

Assuming now the locomotive remains standing and it is desired to operate the injector. The starting valve 9 is opened. With the opening of the starting valve 9, live steam passes through the conduit 8 to the forcing tubes 4 of the injector and, at the same time, live steam passes through the conduit 14, opens the live steam valve 18, passes through the passage 15 and through the outlets 16 into the conduit 10, through which at reduced pressure, due to expansion in the conduit 10, it passes to the heating tubes 3 of the injector.

At the same time, live steam passes through the passage 15 and the choke device 17 and acts on the piston 54 in the cylinder 55, causing the valve 53 to be closed against the action of spring 59, which normally maintains it in open position. Any over rapid closing of the valve 53 is prevented by the dampening effect caused by the passage of oil in the cup 57 through the passage 62 in piston 61 as the cup ascends with respect to the piston in the closing movement of the valve 53. The closing of valve 53 insures that live steam will not pass through conduit 10 toward the exhaust pipe of the engine.

With the opening of starting valve 9 and the provision of live steam in conduit 14, live steam will pass from conduit 14 through conduit 39 and effect opening of the valve 32 for the passage of exhaust steam through conduit 31 to chamber 30. Live steam passing through conduit 39 will effect closure of the check valve 42 and act to lift the piston 38, which will act in its upward movement to lift the valve 32 off of its seat 34 against the action of spring 35.

When the injector is operated with the engine standing, as described above, the heating tubes will be, as has been made clear, supplied with auxiliary live steam. If now the engine be started up and put into action, exhaust steam from the engine will pass into the conduit 10 through conduit 31, valve 32 being open, to chamber 30. The chamber 30 will normally contain water (condensate) to about the level indicated by 78

the line $x-x$ and likewise water will be contained in the casing above the diaphragm. Exhaust steam entering chamber 30 will force water through the passages and apertures in the member 45. The passages and apertures in the member 45 will act to throttle the fluid passing through the aperture 44 to the diaphragm so that a steady supply of exhaust for operation of the injector will be insured before sufficient pressure is built up on the diaphragm 27 to depress the diaphragm with consequent depression and closing of the auxiliary live steam valve 18. Water passing through aperture 44 and acting on the diaphragm will collect in the casing 15 13 above the diaphragm, whereby pressure is built up on the diaphragm compressing the air contained in the casing above the diaphragm (i. e., the space y). With closing of the auxiliary steam valve 18, auxiliary steam will no longer pass 20 through the choke device 17 for action on the piston 54 and the exhaust steam control valve 53 will be opened by the action of its spring 59 with consequent supply of exhaust steam to the tubes 3. The action of the spring 59 will cause 25 the passage of oil in the cup 57 through the aperture in the fixed piston 61 as the cup descends under the influence of the spring.

If the locomotive be again brought to rest, or the throttle be closed, as in drifting and as a result no or insufficient exhaust is available 30 for operating the heating tubes 3, the live steam in conduit 14 will effect opening of the live steam valve 18, the exhaust control valve 53 will be closed and auxiliary live steam will be again supplied to the heating tubes. When exhaust is again available, as on restarting the engine or opening the throttle more or less, the various parts will act as above described to shut off the supply of auxiliary live steam and permit the 40 supply to the heating tubes of exhaust steam.

With more particular reference to the valve 18 and its operation under the pressure of live steam in conduit 14 and by pressure of exhaust steam upon the diaphragm 27, it will be noted 45 that when there is no pressure on the diaphragm 27 live steam will operate under the upper head 18' of the valve 18 and also on the top of the lower head 18''. Since the area of the upper head 18' is greater than the lower head 18'', the 50 valve will readily open under live steam pressure. When the valve 18 starts to open pressure will build up in chambers 70 and 71. The pressure above and below the heads will be less than that between the heads. When the valve 18 is 55 in full open position, it will be noted that the upper seat 20 on its head 18' seats on the seat 21 on the under side of the guide 23 for the valve stem 22, thus reducing the area of the top of the upper head exposed to pressure in the chamber 70 and thereby increasing the effective upward pressure on the valve, thus insuring that it will remain open until closed by the presence of sufficient pressure on diaphragm 27.

A predetermined exhaust pressure operating 60 upon the diaphragm 27, while greatly less than the pressure of the live steam operating on the valve 18, will readily effect a closing of the valve 18 due to the balancing effect of the pressure on the upper and lower heads of the valve, the 65 pressures on which are more nearly balanced when the valve is closed than when it is open due to reduction in effective area of the top of the upper head when seated on seat 21. In practical embodiments of this invention it will be 70 desirable to so proportion the surfaces of the

heads of the valve 18 with respect to the diaphragm 27 and the pressure to be exerted thereon that the valve 18 will open to supply auxiliary live steam to the heating tubes 3 of the injector and will close with supply of exhaust steam 5 on a predetermined drop and rise in pressure on the diaphragm 27.

It will be understood that the above detailed description is of a preferred embodiment of this invention for illustrative purposes and is not to 10 be taken as in any way in limitation thereof, since it will be obvious that various modifications may be made in detail without departing from the scope of the invention.

What I claim and desire to protect by Letters 15 Patent is:

1. In combination with a boiler feed water injector adapted to be operated wholly or partially with exhaust steam, a conduit for the supply of exhaust steam from an engine to the injector, 20 a conduit for the supply of auxiliary steam to the injector from a source of live steam when exhaust steam is not available, a valve in said auxiliary steam conduit for controlling the supply of auxiliary steam to the injector, said valve 25 being at least partially balanced, means whereby when the valve is in fully opened position the force thereon acting to maintain it in fully opened position will be increased as compared to the force acting to open the valve when the 30 valve is in closed and partially open position, a pressure responsive diaphragm mechanically connected to said valve and a passage affording communication between the exhaust from an engine and said diaphragm, said diaphragm being arranged so that the pressure of exhaust steam will be exerted thereon in a direction to close said valve.

2. In combination with a boiler feed water injector adapted to be operated wholly or partially 40 with exhaust steam, a conduit for the supply of exhaust steam from an engine to the injector, a conduit for the supply of auxiliary steam to the injector from a source of live steam when exhaust steam is not available, a valve for controlling the supply of auxiliary steam to the injector, a pressure responsive diaphragm operatively connected to said valve, a passage for fluid 45 communicating with said diaphragm, a conduit affording communication between said passage 50 and the exhaust from an engine and means operative to throttle said passage in the direction of travel of fluid toward said diaphragm and to impose a reduced throttling effect on said passage in the opposite direction when the pressure 55 on said diaphragm exceeds the pressure ahead of said throttling means.

3. In combination with a boiler feed water injector adapted to be operated wholly or partially with exhaust steam, a conduit for the supply 60 of exhaust steam from an engine to the injector, a conduit for the supply of auxiliary steam to the injector from a source of live steam when exhaust steam is not available, a valve for controlling the supply of auxiliary steam to the injector, a pressure responsive diaphragm operatively connected to said valve, a chamber for the 65 reception of exhaust steam, a quantity of liquid in said chamber, a conduit connecting said chamber with the exhaust from an engine, a passage 70 affording communication between said chamber and said diaphragm, and means operative to throttle said passage with respect to the passage of liquid under exhaust steam pressure in a direction from said chamber to said diaphragm 75

and to impose a reduced throttling effect on said passage in the opposite direction when the pressure on said diaphragm exceeds the pressure ahead of said throttling means.

5 4. In combination with a boiler feed water injector adapted to be operated wholly or partially with exhaust steam, a conduit for the supply of exhaust steam from an engine to the injector, a conduit for the supply of auxiliary steam to the injector from a source of live steam when exhaust steam is not available, a valve for controlling the supply of auxiliary steam to the injector, a chamber, a pressure responsive diaphragm mounted within said chamber and operatively connected to said valve, a second chamber for the reception of exhaust steam, a liquid in said chambers, in quantity insufficient to fill the chambers, a conduit connecting said second chamber with the exhaust from an engine and a passage affording communication between said chambers.

5 5. In combination with a boiler feed water injector adapted to be operated wholly or partially with exhaust steam, a conduit for the supply of exhaust steam from an engine to the injector, a conduit for the supply of auxiliary steam to the injector from a source of live steam when exhaust steam is not available, a valve for controlling the supply of auxiliary steam to the injector, a chamber, a pressure responsive diaphragm mounted within said chamber and operatively connected to said valve, a second chamber for the reception of exhaust steam, a conduit connecting said second chamber with the exhaust from an engine, a passage affording communication between said chambers and means for throttling said passage in the direction from said second chamber to said diaphragm, said means being movable to impose a reduced throttling effect on said passage in the opposite direction when the pressure on said diaphragm exceeds the pressure ahead of said throttling means.

45 6. In combination with a boiler feed water injector adapted to be operated wholly or partially with exhaust steam, a conduit for the supply of exhaust steam from an engine to the injector, a conduit for the supply of auxiliary steam to the injector from a source of live steam when exhaust steam is not available, a valve for controlling the supply of auxiliary steam to the injector, a pressure responsive diaphragm operatively connected to said valve, a passage containing a liquid communicating with said diaphragm, a conduit affording communication between said passage and the exhaust from an engine and means operative to throttle said passage in the direction of travel of liquid toward said diaphragm and to impose a reduced throttling effect on said passage in the opposite direction when the pressure on said diaphragm exceeds the pressure ahead of said throttling means.

65 7. In combination with a boiler feed water injector adapted to be operated wholly or partially with exhaust steam, a conduit for the supply of exhaust steam from an engine to the injector, a conduit for the supply of auxiliary steam to the injector from a source of live steam when exhaust

steam is not available, a valve for controlling the supply of auxiliary steam to the injector, a chamber, a pressure responsive diaphragm mounted within said chamber and operatively connected to said valve, a second chamber within the first chamber for the reception of exhaust steam, a liquid in said chambers, a non-liquid elastic medium in said first chamber above the diaphragm, a conduit connecting said second chamber with the exhaust from an engine, and a passage affording communication between said chambers. 5

8. In combination with a boiler feed water injector adapted to be operated wholly or partially with exhaust steam, a conduit for the supply of exhaust steam from an engine to the injector, 15 a conduit for the supply of auxiliary steam to the injector from a source of live steam when exhaust steam is not available, a valve having an upper head and a smaller lower head spaced from the upper head for controlling the passage of auxiliary steam to the injector, a pair of fixed seats for said heads respectively upon which said heads seat in one direction of movement of said valve, a third fixed seat against which the upper head seats in the direction of movement of said valve 25 away from said pair of seats, a chamber above the seat for said upper head and a chamber below the seat for said lower head, a passage affording communication between said chambers, a pressure responsive diaphragm, a conduit affording communication between said diaphragm and the exhaust of an engine and a mechanical connection between said valve and said diaphragm. 30

9. In combination with a boiler feed water injector adapted to be operated wholly or partially with exhaust steam, a conduit for the supply of exhaust steam from an engine to the injector, a conduit for the supply of auxiliary steam to the injector from a source of live steam when exhaust steam is not available, a valve having 40 an upper head and a smaller lower head spaced from the upper head for controlling the passage of auxiliary steam to the injector, a pair of fixed seats for said heads respectively upon which said heads seat in one direction of movement of said valve, a third seat against which the upper head seats in the direction of movement of said valve away from said pair of seats, a chamber above the first mentioned seat for said upper head and a chamber below the seat for said lower head, 45 a passage affording communication between said chambers, a third chamber, a pressure responsive diaphragm mounted within and forming one wall of said third chamber, a fourth chamber located within said third mentioned chamber, a conduit affording communication between said fourth chamber and the exhaust of an engine, a passage affording communication between said third and fourth chambers, a liquid in said third and fourth chambers, a non-liquid elastic medium 50 in the third chamber above the diaphragm, whereby pressures varying in accordance with exhaust steam pressure may be transmitted to the diaphragm and a mechanical connection between said valve and said diaphragm. 55

HERMANN E. F. C. LINGENBRINK.
